UNITED STATES PATENT OFFICE

2,578,799

BANDING MACHINE

Victor A. Grey, Chicago, Ill., assignor, by mesne assignments, to Kartridg-Pak Machine Co., Chicago, Ill., a corporation of Illinois

Application March 30, 1945, Serial No. 585,710

10 Claims. (Cl. 93—3)

1

The present invention has to do with a machine for banding sausages or other articles.

The principal object of the invention is to provide an improved machine of the character described which will automatically effect the banding at a high rate of speed.

The new machine connects the articles together in neatly compacted series of any desired length; applies the banding material snugly and uniformly to the articles, irrespective of minor variations in the size of the same; is comparatively simple in construction; is easy and safe to operate, even by inexperienced labor; is sanitary and readily cleanable; and is inexpensive to manufacture, service and repair.

The new machine is an improvement in a number of important respects over the banding machine disclosed in the copending application of Edward C. Sloan and Wilton F. Hoag, filed June 26, 1942, under Serial No. 448,672 (now Patent No. 2,418,054) and the banding machine disclosed in the copending application of Edward C. Sloan, filed May 8, 1944, under Serial No. 534,666 (now Patent No. 2,379,937).

The new machine is capable of producing band type package structures of the character disclosed in the copending application of Oscar E. Seiferth, filed October 8, 1941, under Serial No. 414,088 (now Patent No. 2,379,934), following in a general way in its operation the banding method disclosed in the copending application of Oscar E. Seiferth and Edward C. Sloan, filed October 8, 1941, under Serial No. 414,089 (now Patent No. 2,379,935), but it will be appreciated that the machine can be readily modified to produce various other package structures in which the articles are continuously banded.

Another object of the invention is to provide in a machine of the character described improved control means for effecting the severing of the banding material after a predetermined number of the articles have been banded and connected together, whereby to obtain a package of any desired length.

Another object is to provide improved means for obtaining a uniform positioning of the articles in the finished package, with their ends even and, in the case of curled sausages, with all of the sausages curled in the same direction.

Still another object of the invention is to accomplish the above mentioned and other objectives by new and useful methods which in and of themselves constitute substantial improvements over the prior art.

While the foregoing statements are indicative

2

in a general way of the nature of the invention, other more specific objects and advantages will be apparent to those skilled in the art upon a full understanding of the new machine and its mode of operation.

A preferred embodiment of the invention is presented herein by way of exemplification but it will of course be appreciated that the invention is susceptible of incorporation in various other structurally modified forms coming equally within the scope of the appended claims.

In this preferred embodiment the machine is designed for the banding of link type sausages, which use presents certain problems peculiar to the handling and banding of sausages, and for which use the invention has been found to be of especially great advantage, but it is to be understood that the machine is readily adaptable to the banding of other articles and that the references hereinafter made to sausages are not to be interpreted in any limiting sense in so far as the broader aspects of the invention are concerned.

In the accompanying drawings:

25 Fig. 1 is a side view of a sausage banding machine constructed in accordance with the invention;

Fig. 2 is a plan view of the machine;

Fig. 3 is a perspective view of a row of sausages which have been banded together by the machine into a unified package structure;

30 Fig. 4 is a fragmentary longitudinal section through one end of the package structure shown in Fig. 3;

35 Fig. 5 is a vertical transverse section through the machine, taken on approximately the line 5—5 of Fig. 1;

40 Fig. 6 is a vertical longitudinal section, taken on approximately the line 6—6 of Fig. 5, showing the banding mechanism at one stage in its operation;

Fig. 7 is a similar section showing the banding mechanism at a later stage in its operation;

45 Fig. 8 is a horizontal section, taken on approximately the line 8—8 of Fig. 6, with certain portions broken away to reveal otherwise concealed features of construction;

Fig. 9 is a transverse section, taken on approximately the line 9—9 of Fig. 8, showing the platen against which the sealing head operates and the blade in the platen for either perforating or severing the banding material;

Fig. 10 is a vertical longitudinal section through the discharge end of the channel member in which 55 the sausage feeding conveyor operates, showing

the device used in rotating curled sausages to place them all in the same position;

Fig. 11 is a vertical longitudinal section, taken on approximately the line 11—11 of Fig. 5, showing the device provided for insuring the machine being brought to a stop with the sealing head in its retracted position;

Fig. 12 is a diametric section through the slip-clutch pulley provided for driving the main operating shaft of the machine, taken approximately on the line 12—12 of Fig. 8;

Fig. 13 is a side view of the device employed for controlling the operation of the cut-off; and

Fig. 14 is a horizontal section through the control device, taken on approximately the line 14—14 of Fig. 13.

The machine illustrated in the drawings is adapted to produce an articulated package on the order of the one shown in Figs. 3 and 4. In this package a predetermined number of link type sausages 10 are individually banded about their centers by encircling loops 11 and are connected together side-by-side by intervening webs 12, in a substantially straight row. The loops and webs are formed from two strips 13 and 14 of paper or other suitable material—the loops 11 about the sausages being composed of complementary strip sections 15 and 16 and the connecting webs 12 being composed of contiguously secured strip sections 17 and 18. The webs 12 are preferably perforated crosswise of the same at 19, midway between adjoining loops, in order to enable any two of the sausages in the unified package to be readily separated from each other by tearing the webs, without disturbing the loops about those particular sausages or any of the other sausages, which loops will remain intact on the separated sausages as identifying bands. The loops 11 may advantageously bear printed matter, such as a trademark, a list of ingredients, directions for cooking, etc. The strips 13 and 14 are preferably, though not necessarily, of the same width and may advantageously be made flexible enough to enable any two of the sausages to be spread apart easily, both for convenience in reaching in to the webs to tear the same and also for convenience in rolling up the row of sausages into compact form for weighing or wrapping.

The machine includes a horizontally elongated main frame 20. The frame 20 provides a mounting for two conveyors 21 and 22, which conveyors extend longitudinally of the frame in substantially end-to-end relation to each other. The conveyor 21 feeds the sausages to the point in the machine where the banding operation takes place, while the conveyor 22 supports the sausages after they have been banded and delivers them to a point where they can be conveniently removed from the machine for boxing or other disposition.

The strips 13 and 14 which are used in the banding operation are preferably narrow ribbons of thin but tough flexible paper, printed with a trade-mark or other matter and coated with a transparent thermoplastic adhesive. These strips are fed from rolls 23 and 24 which are positioned in suitably supported reels 25 and 26.

The banding mechanism is for the most part enclosed within a housing 27, which housing is mounted on the frame 20 above the discharge end of the conveyor 21.

The machine is operated by an electric motor 28 which is located in the lower portion of the frame 20. The motor 28 is secured to a bracket 29 which is pivoted at 30 to the frame. The motor is provided within an extension case 31

with reduction gearing (not shown), which gearing turns a shaft 32 on which a pulley 33 (see Fig. 12) is mounted. The pulley 33 drives a belt 34 which extends upwardly and is trained over another pulley 35. The pulley 35 (see Fig. 5) is secured to a shaft 36 which is journaled in the housing 27. The shaft 36 constitutes the main operating shaft of the machine and makes one revolution for each sausage banding operation. The off-center location of the case 31 and pulley 33 relative to the point of pivotal support 30 places a uniform tension on the belt 34, which tension is sufficient to cause the belt to engage with the pulleys 33 and 35 but is not so great as to prevent slippage in the event any moving part of the machine meets with an obstruction during its operation.

The sausage feeding conveyor 21 is operated from the shaft 36 by a chain 37 which is trained over a sprocket 38 on that shaft. The chain 37 extends downwardly to another sprocket 39 which is secured to a shaft 40 (see Fig. 8) journaled in the frame 20. The shaft 40 carries two spaced sprockets 41 which are located on the shaft at points equidistant from the center line of the machine. These sprockets, which drive the conveyor 21, are provided with parallel chains 42 which extend horizontally to other sprockets 43 mounted on an adjustably positioned shaft 44 at the far end of the machine. The upper stretches of the chains 42 travel toward the banding station in and upon an upwardly opening channel member 45. At regular intervals the links of the chains 42 are provided with upwardly opening holders 46 in which the opposite ends of the sausages to be banded are adapted to be placed with the sausages disposed crosswise of the conveyor. The channel member 45 terminates at 47 adjacent the discharge end of the conveyor 21, and at this point the holders 46 on the chains move downwardly in an arc, releasing each of the sausages in turn. As the holders 46 move downwardly the ends of the sausages carried by the same are deposited on laterally spaced transfer plates 49, which plates are located with their upper surfaces substantially even with the bottoms of the holders 46 during the horizontal travel of the latter.

The conveyor 22 which is positioned with its receiving end just beyond the ends of the transfer plates 49 is formed in two sections 50 and 51. The first section 50 consists of two side plates 52 which are connected in spaced parallel relation to each other by tie rods 53. The upper edges of the side plates 52 extend first upwardly and rearwardly at a slight inclination to the horizontal and then downwardly and rearwardly at a slight inclination to the horizontal. These inclined edges of the side plates are provided with small bearing apertures in which the reduced ends of anti-friction rollers 54 are journaled. The rollers 54 are arranged in practically continuous side-by-side relation to provide a substantially flat supporting surface for the reception and advancement of the banded sausages.

The front section 50 of the roller conveyor is removably positioned in the frame of the machine on two spaced guide rails 55, which rails permit the section to be withdrawn rearwardly to give ready access for cleaning. The section 50 is normally held against rearward movement by small locking studs 56 on the side rails, which studs extend upwardly into complementary recesses in the lower edges of the side plates 52.

The rear section 51 of the roller conveyor likewise consists of side plates 57, tie rods 58 and

anti-friction rollers 59. The rear section is arranged as a continuation of the front section, at the same downwardly sloping inclination as the adjacent portion of the front section, which inclination is variable and is so adjusted as to cause the banded sausages to gravitate down the same under their own weight. The rear section is removably supported on underlying rails 60, which rails are pivotally connected at their front ends at 61 to the rails 55 to permit the section 51 to be either removed or else dropped downwardly into an out-of-the-way position. The section 51 is normally held in its inclined position by diagonally arranged braces 62, which braces are pivoted at their upper ends to the rails 60 at 63 and are adjustably secured at their lower ends to adjacent portions of the frame 20 by bolts 64 engaging within elongated slots 65 in the frame. The section 51 is releasably secured in position on the supporting rails 60 by the clamping action of a set screw 66.

The sausages when being placed in the longitudinally spaced holders 46 of the sausage feeding conveyor may be conveniently taken from a tray 67 mounted on the frame along one side of the channel member 45.

The mechanism which effects the banding of the sausages is located for the most part within the housing 27 on the upper part of the frame of the machine. This mechanism includes primarily a stationary platen 68 over which the two strips 13 and 14 of banding material are fed; a movable sealing head 69 which operates against the platen to secure the interposed strips together; a pair of movable sausage positioning hooks 70 which place each sausage in turn in proper position between the strips of banding material; a movable strip curling blade 71 which wraps the upper strip about each sausage after the latter has been placed between the strips; and a movable band perforating and cutting blade 72, which blade perforates both strips in the sealed connecting web portions thereof and at predetermined times completely severs both strips.

The platen 68 (see particularly Figs. 6, 7, 8 and 9) is set at a forwardly tilted angle in a position just in advance of the receiving end of the front section 51 of the roller conveyor, between the laterally spaced transfer plates 49. The platen is resiliently yieldable to a limited extent in a direction normal to the plane at its upper surface against the resistance of underlying springs 73. The springs are positioned between the platen and an underlying block 74, in recesses 75 in the latter, and the upward projection of the platen is limited by nuts 76 on bolts 77, which bolts also serve to guidingly support the platen in its movement toward and away from the block 74. The platen 68 contains a narrow transversely elongated slot 78, in which slot the perforating and severing blade 72 is slidably mounted with its cutting edge 79 flush with face 80 of the platen in the undepressed position of the latter. The block 74 which carries the platen 68 is provided with a bore 81 in which a rod 82 connected with the blade 72 is slidably guided. The lower edge 83 of the blade 72 normally rests against the upper surface of the block 74. The upper or cutting edge 79 of the blade 72 is notched out at 84 to cause the blade to perforate without completely severing the overlying strips of the banding material upon the platen 68 being depressed into solid abutment with the block 74. When it is desired to have the overlying strips of band-

ing material completely severed, however, the rod 82 connected with the blade 72 is advanced in the block 74, causing the blade 72 when the platen is depressed to project far enough into the banding material to present a continuous cutting edge from one end to the blade of the other. The means provided for elevating the blade 72 from its normal perforating position to its raised severing position, at predetermined intervals, will be described later.

The sealing head 69 (see Figs. 6 and 7) is a block-like member which tapers toward its lower end and is characterized at that end by a pressure face 85. The face 85 is elongated in a direction crosswise of the machine and is provided intermediate its front and rear edges with a narrow groove 86, which groove receives the upper edge 79 of the perforating and severing blade 72 when the sealing head is moved downwardly into engagement with the portions of the strips 13 and 14 resting on the platen 68. The head 69 is heated by an electric heating element (not shown) which is enclosed within the same, and the heating element is connected by flexible leads 87 with a source of current. The head 69 moves between a lowered position and a raised position. In its lowered position it registers with the face 88 of the platen 68 and is disposed at a downwardly and rearwardly inclined angle, with its face 85 at the same angle to the horizontal as the face 86 of the platen. The sealing head 69 is located midway between the side plates 88 of the housing 27 and is mounted on the front end of an arm 89 which extends forwardly from a stationary cross rod 90. The arm 89 is journaled at its rear end on the rod 90 for oscillation on a vertical plane and is provided on its upper side with a cam following roller 91. The roller 91 engages with a cam 92 which is secured to the shaft 36. The cam 92 acts to move the arm 89 downwardly, while a tensioned coil spring 93 which extends upwardly from the arm to a stationary cross rod 94 acts to return the arm to its elevated position under the restraining control of the roller 91.

The two laterally spaced sausage positioning hooks 70 (see Figs. 6 and 7) are located in the housing 27 at opposite sides of the sealing head 69, for engagement with the end portions only of each sausage. The hooks 70 are curved rearwardly and are secured at their upper ends to the front ends of horizontally disposed arms 95. The arms 95 are rigidly connected together in spaced parallel relation by short tie rods 96, and are pivotally connected at their rear ends to the lower ends of upwardly extending links 97. The links 97, which are similarly connected together by short tie rods 98, are pivotally connected at their upper ends to a stationary cross rod 99. A cam 50 following roller 100 is journaled on the side of one of the links 97 and engages with a cam 101 which is secured to the shaft 36 at one side of the sealing head cam 92. The roller 100, acting through the links 97, operates to move the hooks 55 70 rearwardly, while two tensioned coil springs 102, which extend forwardly from the links 97, operate to return the hooks to their forwardly disposed positions. During their rearward movement the hooks are lowered by the action of a bell crank lever 103 which is journaled on the rod 90. One of the arms 104 of the lever 103 carries a roller 105 which rides in a horizontally elongated slot 106 in one of the arms 95, while the other arm 107 of the lever 103 carries a cam 60 75 following roller 108 which engages with a third

cam 109 on the shaft 36. During the return or forward movement of the hooks 70 the latter are raised and maintained in an elevated position by a tensioned coil spring 110, which spring extends upwardly from the arm 104 of the lever 103 to a stud 111.

The curling blade 71 (see Figs. 6 and 7) which acts to abruptly tuck the upper strip 13 down behind each sausage into a position over the platen 68 for engagement with the sealing head 69, is located immediately to the rear of and in alignment with the sealing head. The blade 71 is curved rearwardly and is secured at its rear end to a rock shaft 112. The shaft 112 is journaled at its ends in the side plates 38 of the housing and is provided near one of its ends with a short forwardly extending arm 113. The arm 113 is pivotally connected at its forward end with the lower end of an upwardly extending link 114, and the link 114 is pivotally connected at its upper end to the front end of another link 115. The link 115 is pivoted at its rear end to the cross rod 99 and is provided intermediate its ends with a cam following roller 116 which engages with a fourth cam 117 on the shaft 36. The cam 117 acts to raise the blade 71 into an elevated out-of-the-way position, while a tensioned coil spring 118 which extends between studs 119 and 120 carried at a suitable point on the machine housing and by the link 114, respectively, acts to move the blade 71 downwardly to draw the upper strip 13 into place behind the sausage being operated on in readiness for descent of the sealing head 69.

The lower strip 14 in traveling from the reel 26 to the platen 68 passes upwardly and rearwardly along a slide plate 121 (see Fig. 6). The plate 121 is provided at its upper end with a flattened tubular portion 122 which directs the strip onto the platen, and is provided below the tubular portion 122 with a tensioning device 123 for yieldingly resisting the movement of the strip toward the platen. This device consists of a small bracket 124 which is pivoted at its upper end to the plate 121 and is provided with a weighted roller 125, which roller rides on the strip 14 and presses the latter snugly against the plate. The weight of the roller 125 tends to swing the lower end of the bracket 124 away from the plate 121. The bracket 124 is adjustably connected by a screw 126 to a friction shoe 127 which overlies the strip 14, with the result that upward movement of the strip is yieldingly resisted to the extent determined by the adjustment placed on the tensioning device by the setting of the screw.

The upper strip 13 in traveling from the reel 25 to the platen 68 passes first through two flattened guide loops 128 and 129, which loops are mounted on an oscillating arm 130. The arm 130 extends forwardly and upwardly from the front end of the housing 27 and is secured to a rock shaft 131, which shaft is journaled at its ends in the housing. The shaft 131 is rocked back and forth by a link 132 which is pivotally connected at its front end to a lever 133 on the shaft 131 and is pivotally connected at its rear end to an intermediate portion of one of the links 97. The movement of the loops 128 and 129 acts to draw a short length of the strip 13 from the reel 25 for each banding operation. From the lower loop 129 strip 13 is threaded between a bracket 134 on the housing 27 and a weighted roller 135 carried by a plate 136 hinged to the bracket. The weight of the roller 135

tends to press the strip 13 snugly against the opposite face of the bracket 134, producing just enough tension on the strip to keep the latter taut while it is being tucked down behind each sausage by the curling blade 71, which thus acts to hold the adjacent sausage in place as the banding operation proceeds.

The operation of those parts of the banding mechanism thus far described is as follows:

Assuming that portions of the upper and lower strips 13 and 14 have been moved into a position overlying the platen 68—rotation of the shaft 36 causes the heated sealing head 69 to descend alongside the then lowered curling blade 71 onto the strips (as shown in Fig. 7) and press the latter tightly against the platen. The heat and pressure to which the strips are thus subjected act on the adhesive on the strips to securely bond the same together across their entire widths, throughout a rectangular area corresponding to the shape of the face 85 of the sealing head, producing from the sections 17 and 18 of the strip the desired connecting web 12 (see Fig. 4). As the sections 17 and 18 of the strips are being bonded together the platen 68 yields downwardly far enough to expose through the upper surface 39 of the same the interrupted portions of the cutting edge 79 of the blade 72, causing the exposed portions to perforate the web 12 at 19.

Further rotation of the shaft 36 then causes the sealing head 69 to move upwardly into an out-of-the-way position and the hooks 70 to move downwardly into engagement with the rear-most sausage on the conveyor 21 just as that sausage is being disengaged by the then downwardly moving holders 46 of the conveyor and deposited with its ends resting on the laterally spaced transfer plates 49.

Still further rotation of the shaft 36 then causes the hooks 70 to move rearwardly with the sausage, shifting it against the free bight 137 of the upper strip 13. This causes the strip to be advanced against the yielding resistance offered by the retarding roller 135, which resistance is sufficient to cause the bight 137 of the strip to be looped rather closely about the advancing face of the sausage. This rearward movement of the sausage into engagement with the bight 137 brings the sausage into engagement with the previously banded sausage, shifting the latter and all banded sausages before it along the conveyor, leaving the sausage which is to be banded in the position formerly occupied by the last banded sausage.

It has been found convenient, in boxing continuously banded sausages, to band the sausages together in rows of anywhere from twelve to seventeen sausages, the number of sausages in each row depending on such factors as the size of the sausages, the length of the boxes, and the total weight desired per box. As previously described, the sausages as they are banded are separated into rows of any desired length by the blade 72, which blade at all other times merely serves to perforate the webs 12 between the sausages.

The means for causing the blade 72 to sever any particular one of the webs 12 and the means for selectively controlling the operation of the blade, will now be described.

The vertically movable rod 82 (see Fig. 9) to which the blade 72 is attached is connected by an adjustable screw connection 138 (see Fig. 6) to the upper end of a rocker arm 139. The arm

139 is pivotally mounted intermediate its ends on a stationary bracket 140, and is connected by a link 141 with the armature 142 of a solenoid 143. When the solenoid 143 is energized the blade 72 will be projected upwardly into a position above the face 80 of the platen 68, in which position it will completely sever the overlying web 12 while the latter is being bonded by the sealing head 69. At all other times the blade 72 will be retained in its lowered perforating position in the platen 68 by a tensioned coil spring 144 connected with the arm 139.

The particular web forming operation at which the solenoid 143 is caused to elevate the blade 72 is controlled by a device 145 which is mounted in a casing 146 on one side of the housing 27 (see Figs. 1 and 2). One end of the operating shaft 36 extends into the casing 146 and is provided with a cam 147. The cam 147 engages with a roller 148 (see Figs. 13 and 14) on one end of an arm 149. The arm 149 is pivotally mounted at its other end on a tubular shaft 150, and the shaft 150 is journaled on a stationary supporting rod 151. The shaft 150 is provided with a ratchet wheel 152, and the arm 149 is equipped with a pivotally mounted dog 153 which engages with each of the teeth of the wheel 152 in turn. Every time the cam 147 moves the arm 149 the wheel 152 is rotated in one direction the distance covered by one of the teeth. Rotation of the wheel 152 in the opposite direction is prevented by a dog 154 which is pivotally attached to a portion of the casing in overrunning engagement with the teeth. As a result of this arrangement, the tubular shaft 150 is caused to turn but one complete revolution during a number of revolutions of the shaft 36.

The tubular shaft 150 carries a sleeve 155 which is slidable axially of the shaft 150 but is prevented from turning relative to the same by a spline connection 156. The sleeve 155 is provided at one of its ends with a gear 157, which gear is adapted to mesh selectively with any one of a plurality of pinions 158, 159, 160, 161, 162 and 163. These pinions are of graduated diameters and are all fixedly mounted on a tubular shaft 164. The shaft 164 is in turn rotatably mounted on a rod 165. The rod 165 is arranged parallel to the axis of the gear 157 and is secured at its ends in the sides 166 of a movable bracket 167. The bracket 167 is pivotally supported at its lower end on a stationary stud 168 and is pressed resiliently toward the gear 157 by a tensioned coil spring 169, whereby to maintain the gear 157 in mesh with the particular pinion opposite the same.

To change from one pinion to another in order to alter the gear ratio between the tubular shafts 150 and 164, the bracket 167 is first swung away from the gear 157 by the depression of an exposed finger piece 170 on a rod 171, which rod extends downwardly through the top of the casing 146 and bears at its lower end against a cross rod 172 on the bracket 167. With the bracket 167 held temporarily in this position, the gear 157 can be shifted axially one way or the other into opposition with any desired one of the pinions, the shifting being effected by means of an accessible handle 173 which is connected with a vertically extending shaft 174. The shaft 174 is journaled in the upper wall of the casing 146 and is provided at its lower end with a lever 175 having a bifurcated block 176 rotatably mounted in its free end. This block loosely embraces the edge of the gear 157, causing the gear to

shift axially in the direction and to the extent that the handle 173 is moved. A downwardly spring pressed detent in the handle 173 is adapted to snap into any one of several arcuately arranged recesses 178 in a plate 179 on the top of the casing 146, whereby to accurately index the gear 157 in direct opposition to the particular pinion to be driven by the same.

The tubular shaft 164 to which the graduated pinions are secured is provided at one of its ends with a circular disk 180 in which a notch 181 is formed. A micro-switch 182 is mounted on the bracket 167 opposite the disk 180 and is provided with an actuating finger 183. The finger 183 is pivotally supported at its upper end and is provided at its lower end with a small roller 184 which rides on the periphery of the disk 180. Intermediate its ends the finger 183 is operatively associated with the circuit closing element 185 of the switch. When the disk 180 is rotated into a position where the notch 181 in the same is directly opposite the roller 184 the latter will spring into the notch and the resulting movement of the finger 183 to the left will momentarily close the switch 182. The switch 182 is arranged in the circuit of the solenoid 143, and the blade 72 will accordingly be elevated at that instant into its severing, as distinguished from perforating, position. The switch 182 can be rendered inoperative, if desired, by opening a second exteriorly accessible switch 186 in the same circuit.

By locating the depressible finger piece 170 adjacent the laterally movable handle 173, as shown, the attendant can change the cut-off adjustment with one hand, by depressing the finger piece 170 with the palm or side of the hand while swinging the handle 173 from one indexing notch to another.

The various gear ratios obtainable by shifting the gear 157 into engagement with the different pinions 158 to 163, inclusive, enables the tubular shaft 164 on which the pinions and the switch operating disk 180 are mounted to make one complete revolution for different numbers of revolutions of the operating shaft 36, whereby to cause the cut-off device to operate at different intervals. When the pinion 158, for example, is engaged by the gear 157, the cut-off device will be operated after a predetermined number of the articles have been continuously banded together, whereas when the pinion 163 is engaged the cut-off device will operate after a lesser number of the articles have been banded. Use of the intervening pinions will produce packages in which correspondingly different numbers of articles are banded.

If for any reason it is desired to individually band the sausages or other articles without coupling them together into a unified package structure, this can be done by elevating a finger piece 187 located beneath the bottom of the casing 146. The finger piece 187 is secured to the lower end of a rod 188 which extends upwardly through the bottom of the casing and is pivotally connected to a horizontally extending link 189. The link 189 is provided at one of its ends with a roller 190 which is adapted to be engaged by a second cam 191 on the shaft 36 when the link 189 is raised to bring the roller into operative relation to that cam. The link 189 is provided with an upwardly extending projection on which an anti-friction roller 192 is mounted. When the rod 188 is shifted upwardly by the finger piece 187 and moved laterally to cause a notch 193 in the

side of the rod to lock the same in its elevated position, the roller 192 will engage with the underside of the arm 193 and lift the roller 193 on that arm into an inoperative position relative to the cam 147. Upon each revolution of the shaft 36 the roller 193 on the link 189 will cause the link to move toward the right. The other end of the link 189 is pivotally connected to the lower end of an upwardly extending rocker arm 194. The arm 194 is pivoted intermediate its ends to a stud 195 and is provided at its upper end with a small anti-friction roller 196 which bears against the switch finger 183 at a point between the pivotal mounting of the latter and the roller 194. The finger 183 is made of spring metal, with the result that the movement of the link 189 and rocker arm 194 upon each revolution of the shaft 36 will flex the finger 183 and cause the switch 182 to close, resulting in the blade 72 being elevated into its severing position during each banding operation.

It is important that the sausages or other articles be delivered by the conveyor 21 to the banding mechanism with the ends of the sausages substantially even with each other and, in the case of sausages which have a pronounced curl, with the curl turned in substantially the same direction, otherwise a package of rather irregular shape will result.

Because of the rapidity with which the conveyor 21 moves it is difficult for those loading the sausages onto the conveyor to place them in the holders 46 with any degree of uniformity of positioning. To obtain a uniform positioning of the ends of the sausages at the delivery end of the conveyor 21 a pair of horizontally extending fingers 197 are provided in the channel member 45 near the end of the same at opposite sides of the conveyor chains 42 (see Fig. 2). These fingers are secured to the upper ends of vertically extending rock shafts 198 which are journaled in apertures in the channel member. Beneath the channel member the shafts 198 are provided with short levers 199 which are connected by links 200 with a centrally arranged slide plate 201 (see Fig. 8). The plate 201 is mounted for horizontal movement in a guideway 202 and is urged in one direction by a spring 203. At one end the plate 201 is provided with a nose portion which is adapted to be engaged by first one and then the other of two diametrically opposed rollers 204. The rollers 204 are carried by a small spider 205 which is secured to the shaft 43 (see Fig. 6). Every time one of the rollers 204 engages the nose portion it slides the plate 201 backwardly against the resistance of the spring 203. As soon as the roller releases the nose portion the spring slides the plate forwardly, causing the front ends of the fingers 197 to move toward each other to the same extent. The movement of the fingers 197 is so timed as to cause the fingers to engage with the ends of a sausage passing the same on the conveyor 21, thereby accurately centering the sausage on the conveyor. The fingers 197 are preferably made of resiliently yieldable spring material in order to allow them to flex enough to compensate for sausages of greater than average length.

To position all of the sausages with the curl therein directed downwardly in a vertical plane, a narrow longitudinally extending trip plate 206 is secured to the channel member 45 midway between the chains 42 (see Fig. 10). The plate 206 projects upwardly from the channel member to a point where it will engage with the center

portions of any sausages which are not already curled downwardly. The engagement of the plate with those sausages will cause the same in passing to rotate into a downwardly curled position. Beyond the plate 206 a second somewhat similar upwardly and rearwardly inclined plate 207 is provided (see Figs. 8 and 10). The plate 207 is inclined upwardly toward the platen 68 and forms an approach to the latter. It is recessed at 208 to afford sufficient clearance for the entrance of the lower strip 14.

To insure the machine always coming to a stop with the sealing band 69 in its elevated position, a stop 209 is secured to one end of the operating shaft 36 for abutment with one end 210 of a dog 211 (see Fig. 11). The dog 211 is pivotally mounted intermediate its ends on a stud 212 which projects from the adjacent side of the housing 27 and is connected at its other end by a link 213 to the armature 214 of a solenoid 215, which solenoid is arranged in the circuit of the operating motor 28. As long as the motor 28 is operating the solenoid 215 will be energized and will hold the end 210 of the dog 211 in an elevated position clear of the rotating stop 209, but as soon as the motor 28 is turned off the end 210 of the dog will drop downwardly into the path of movement of the stop 209, under the action of a tensioned coil spring 216 and the natural tendency of the shaft 36 to turn a few additional revolutions before coming to rest will insure the stop 209 coming up into abutment with the end 210 of the dog. The dog will then cause the shaft 36 to be brought to an abrupt stop in a position in which the sealing head 69 will be in its elevated, as distinguished from depressed, position.

Should anything interfere at any time with the normal operation of the machine—as for example a sausage getting inadvertently placed on the conveyor 21 at an angle instead of cross-wise—the banding mechanism upon meeting the additional resistance caused by the obstructing sausage will come to a stop without any damage being done to the mechanism. This is possible due to the mounting of the motor 28 so that it is capable of yielding upwardly to momentarily release the tension on the belt 34, and is further insured by introducing a slip clutch 217 into the driving pulley 33. The pulley 33 includes a centrally grooved ring 218 which is rotatable relative to the hub 219 of the pulley and two side plates 220 which are non-rotatably keyed to the hub. Friction disks 221 of any suitable material are positioned under adjustable compression between the side plates 220 and the grooved ring 218 for yieldingly resisting relative rotation therebetween under overloading conditions, the amount of torque transmitted being determined by the adjustment of clamping nuts 222. The side plates 220 are thinned out at 223 and the resulting resiliency is utilized to place the friction disks 221 under spring pressure. The disks 221 are apertured at 224 to permit grease packed in the pulley to work to the journaling portion of the ring 218.

The operation of the banding mechanism of the machine, briefly summarized, is as follows:

After the upper strip 13 has been brought down onto the lower strip 14 on the platen 68 by the action of the strip positioning blade 71 the sealing head 69 descends onto the strips and the heat in the head bonds the two strips together to form one of the webs 12. At the same time the web 12 is perforated by the action of the blade 72 in the platen. The sealing head 69 and blade 71 then rise into an out-of-the-way

position, and the sausage engaging hooks 70 descend into engagement with the ends of the foremost sausage on the conveyor 21 and slide that sausage along the transfer plates 49 and over the platen 68 between the converging portions of the strips 13 and 14. The engagement of the sausage with the strips 13 and 14 at the edge of the web 12 acts to push the strips into a position beyond the platen 68. The hooks 70 bring the sausage from the position in Fig. 6, to rest against the last previously banded sausage, in approximate sidewise abutment with the latter. The resistance offered by the strip tensioning device 123 to the advancement of the strip 14 maintains the latter in a taut condition over the platen 68, while the resistance offered by the strip tensioning roller 135 to the advancement of the strip 13 maintains that strip snugly drawn about the advancing face of the sausage. As soon as the sausage has reached the position in sidewise abutment with the previously banded sausage, the strip positioning blade 71 will descend to wrap the upper strip 13 about the sausage and depress such strip into a position adjacent the strip 14 on the platen 68 as illustrated in Fig. 7. While this is occurring the sealing head 69 descends and bonds the two strips together behind the sausage, in a second web 12, thereby completing the banding of the sausage. While the sealing head 69 is in its depressed condition, the platen 68 yields downwardly far enough to permit the normally concealed blade 72 in the platen to perforate the web 12 intermediate the front and rear edges of the latter. The hooks 70 then release the banded sausage, rise far enough to clear the next sausage, then descend into engagement with that sausage, which is located as shown in Fig. 6, and move the latter to sidewise abutment with the preceding sausage, the series of already connected sausages on the front section 50 of the conveyor 22 being pushed forwardly as a unit a distance approximately equal to the diameter of each sausage. The upward inclination of the front portion of the first section 50 of the conveyor offers some resistance to the advancement of the connected sausages, which resistance assists in obtaining a compact packaging structure.

Should one of the sausages be placed wrong on the conveyor 21 and the sealing head 69 become wedged against the same, causing the machine to stop, the machine can be cleared by shutting off the motor 28 and reversing the shaft 40 part of a turn by means of a hand crank applied to a crank socket 225 at one end of that shaft. Reversal of the shaft 40 will raise the sealing head, permitting removal of the obstructing sausage.

It will be apparent from the foregoing description that the structure herein disclosed is merely exemplary of various provisions for attaining the same ends, which will readily suggest themselves to those skilled in the art, both for the banding of articles with a pair of bands or for other manipulations involving the same or a different number of strips. I therefore desire that the invention be construed no more narrowly in these respects than is indicated in the appended claims.

I claim:

1. In a machine for automatically banding articles, means for supplying banding material, a platen across which portions of the banding material are adapted to be positioned while being secured together, means for feeding the articles to be banded, means for moving each of the articles into a position beyond the platen with

portions of the banding material about the article and other portions of the banding material across the platen, a sealing head which is movable into engagement with the platen behind the article on the interposed portions of the banding material for securing such portions together, a motor for operating the sealing head, and means for stopping the movement of the sealing head in a retracted position when the motor is shut off.

2. In a machine for automatically banding articles, means for supplying banding material, a platen across which portions of the banding material are adapted to be positioned while being secured together, means for feeding the articles to be banded, means for moving each of the articles into a position beyond the platen with portions of the banding material about the article and other portions of the banding material across the platen, a sealing head which is movable into engagement with the platen behind the article on the interposed portions of the banding material for securing such portions together, a shaft connected with the sealing head for moving the latter, a motor for operating the shaft, an abutment carried by the shaft, a stop cooperable with the abutment to bring the shaft to rest with the sealing head in a retracted position, and means for normally rendering the stop inoperative, said means being connected with the circuit of the motor and serving to permit movement of the stop into an operative position upon the motor being shut off.

3. In a machine for automatically banding articles, a banding mechanism, means for supplying banding material to the mechanism, a conveyor for feeding the articles to be banded to the mechanism and periodically operable means shiftable transversely of the path of feed of said articles by said conveyor and into engagement with the ends of the articles while on the conveyor for centering the articles on the conveyor prior to their delivery to the banding mechanism.

4. In a machine for automatically banding articles, of the type including a banding mechanism, means for supplying banding material to the mechanism, and a conveyor for feeding the articles to be banded to the mechanism, means engageable with the ends of the articles while on the conveyor for centering the articles on the conveyor prior to their delivery to the banding mechanism, said centering means consisting of a pair of pivoted fingers, and means for moving the free ends of the fingers into engagement with the ends of the articles.

5. In a machine for automatically banding articles, of the type including a banding mechanism, means for supplying banding material to the mechanism, and a conveyor for feeding the articles to be banded to the mechanism, means engageable with the ends of the articles while on the conveyor for centering the articles on the conveyor prior to their delivery to the banding mechanism, said centering means consisting of a pair of pivoted fingers, and means for moving the free ends of the fingers into engagement with the ends of the articles, said fingers being resiliently flexible and yieldable to compensate for articles of varying length.

6. In a machine for automatically banding curled articles such as link type sausages into a package structure, a banding mechanism, means for supplying banding material to the mechanism, a conveyor for feeding the articles to be

banded to the mechanism, and means engageable with each of the articles on the conveyor for positioning the article with the curl in the same plane.

7. In a machine for automatically banding curled articles such as link type sausages into a package structure, a banding mechanism, means for supplying banding material to the mechanism, a conveyor for feeding the articles to be banded to the mechanism, and means engageable with each of the articles on the conveyor for positioning the article with the curl in the same plane, said article engaging means consisting of a trip in the path of movement of the articles, which trip engages and rotates into the desired position only those articles which are not already in that position.

8. In a machine for automatically banding elongated articles, means for supplying banding material, means for feeding articles to be banded, a platen across which portions of the banding material are fed, means engageable with the ends of the articles while on said last named means for centering the articles thereon, means for forming the banding material into loops about the articles and connecting webs between the loops which are disposed across said platen, a sealing head movable into engagement with the platen at said connecting webs, a motor for operating said sealing head, means for stopping the movement of said sealing head in a retracted position when the motor is shut off, means mounted in the platen for cutting said web, means for controlling the operation of said cutting means, comprising a drive shaft operating in timed relation to said loop forming means, a driven shaft operating in timed relation to the cutting means, a power transmitting means between said shafts, and means for varying the speed ratio of said power transmitting means.

9. In a machine for automatically banding elongated articles, means for supplying banding material, means for feeding articles to be banded, a platen across which portions of the banding material are fed, means engageable with the ends of the articles while on said last named means for centering the articles thereon, means for forming the banding material into loops about the articles and connecting webs between the loops which are disposed across said platen, a sealing head movable into engagement with the platen at said connecting webs, a motor for operating said sealing head, means for stopping the movement of said sealing had in a retracted position when the motor is shut off, means mounted in the platen for cutting said web, means for controlling the operation of said cutting means, comprising a drive shaft operating in timed re-

lation to said loop forming means, a driven shaft operating in timed relation to the cutting means, a power transmitting means between said shafts, means for varying the speed ratio of said power transmitting means, and a conveyor for receiving articles after they have been banded, said conveyor being provided with a supporting surface composed of a plurality of closely arranged anti-friction idler rollers.

10. In a machine for automatically banding elongated curled articles, means for supplying banding material, means for feeding articles to be banded, means engageable with the articles on said last named means for centering the articles thereon and for positioning the articles with the curl in the same plane, a platen across which portions of the banding material are adapted to be positioned while being secured together, means for forming the banding material into loops abut the articles and connecting webs between the loops which are disposed across said platen, a sealing head movable into engagement with the platen at said connecting webs, means mounted in the platen for cutting said web, said means being movable relative to the platen from one position in which it perforates said webs to another position in which it completely severs the same, means for controlling the operation of said cutting means, comprising a drive shaft operating in timed relation to said loop forming means, a driven shaft operating in timed relation to the cutting means, a power transmitting connection between said shafts, means for varying the speed ratio of said power transmitting means, and a conveyor for receiving articles after they have been banded, said conveyor being provided with a supporting surface composed of a plurality of closely arranged anti-friction idler rollers.
